UNITED STATES PATENT OFFICE.

WILLIAM E. BEATTY, OF BAYSIDE, NEW YORK, ASSIGNOR TO WESTERN ELECTRIC COMPANY, INCORPORATED, OF NEW YORK, N. Y., A CORPORATION OF NEW YORK.

SIGNALING SYSTEM.

Application filed November 6, 1917. Serial No. 200,493.

To all whom it may concern:

Be it known that I, WILLIAM E. BEATTY, a citizen of the United States, residing at Bayside, Long Island, in the county of 5 Queens and State of New York, have invented certain new and useful Improvements in Signaling Systems, of which the following is a full, clear, concise, and exact description.

10 The present invention relates to a signaling system in which modulated high frequency carrier currents are employed for transmitting the messages through space or over wires and the invention especially refers to an improved system for effecting the 15 modulation or modification of the carrier wave in accordance with the signals.

As described, page 145 et seq., of a publication written by Miessner on Radiodynam- 20 ics, it is very desirable to obtain at the sending station a carrier wave modulated in such a manner that it is possible to use, at the receiving station, apparatus which is highly responsive to the wave transmitted 25 at its corresponding signaling station, but is unresponsive to waves from other sources. The sending station described in the above named publication employs one generator for supplying a carrier wave having a high 30 frequency and another generator for supplying another carrier wave of lower frequency. A telegraph key is so associated with the two generators that the station sends out a wave of the higher frequency modulated in 35 accordance with a modulated wave, the latter being the carrier wave of lower frequency modulated in accordance with the signal. This makes it possible to use at the receiving station two detectors connected in

40 tandem, the input circuit of the first detector being tuned to the higher carrier frequency, the input circuit of the second detector being tuned to the lower carrier frequency, and the output circuit of the second detector containing the audible signal- 45 ing frequency. The use at the receiving station of two high frequency circuits tuned to different frequencies is conducive to high selectivity.

50 In this specification a wave transmitted by the Miessner and similar systems will be termed a doubly modulated wave in order to differentiate it from a wave of a single carrier frequency modulated in the ordinary manner. It is also possible to obtain a dou-

ly modulated wave by means of two vacuum tubes connected in tandem as described in British Patent 146,988.

An object of the present invention is to provide a system in which a single modulator is employed for effecting the double modulation. This may be accomplished by means of a vacuum tube of the audion type. A carrier wave of high frequency is supplied to the tube and is transmitted with an efficiency which depends on the impedance in the tube circuit. The carrier wave of low frequency is also supplied to the tube. If only these two sources of waves were present the result would be that the high carrier 60 frequency would be modulated with the low carrier frequency. A signaling device, however, controls the effect of the waves of lower carrier frequency, and the wave of higher carrier frequency is accordingly modulated 65 in accordance with the wave of lower carrier frequency, the latter being in turn modulated by the signal. Incidentally the signaling device serves to modulate the carrier waves individually as well as collectively so 70 that there are present singly as well as doubly modulated waves.

Some of the systems which may be employed for carrying out the present invention are shown in the drawings, in which 85 Fig. 1, illustrates a modulating system in which both sources of carrier waves are supplied to the input circuit of the modulator.

Fig. 2 is a modification of Fig. 1 wherein 90 one carrier wave generator is associated with the input circuit, the other carrier wave generator being associated with the output circuit of the modulator.

Fig. 3 is another modification in which 95 both carrier wave generators are associated with the output circuit of the modulator.

In Fig. 1, f_1 and f_2 are suitable generators of high and comparatively low carrier frequencies F_1 and F_2 , respectively. These two 100 generators are connected to the input circuit of the vacuum tube modulator 1 of the audion type by means of the transformers 2 and 3 respectively.

In case it is desired to transmit telephonic 105 rather than a telegraphic signal, a circuit comprising the transmitter 4 and battery 5 may be coupled to the input circuit of the vacuum tube 1 by means of the transformer 6. The output circuit of the vacuum tube 1 con- 110

tains the usual impedance 7, space current battery 8, and condenser 9 for shunting the high frequency currents around the battery 8. The output circuit of the modulator 1 also includes the circuit LC, which is tuned either to the frequency $F_1 + F_2 \pm S$ or $F_1 - F_2 \pm S$ if the doubly modulated wave is to be transmitted. If a singly modulated wave is to be transmitted, however, then the circuit LC is tuned to either the frequency $F_1 \pm S$ or $F_2 \pm S$. If the doubly modulated wave is transmitted, it may be desirable to choose for F_1 and F_2 values such that the sharpness of tuning of the circuit LC will permit that substantially none of the singly modulated wave will be also transmitted. The circuit LC is coupled to a suitable sending conductor such as the antenna circuit 10.

Fig. 2 illustrates a modification in which one of the generators f_1 or f_2 , it matters not which, is coupled to the output circuit of the tube 1 by means of the transformer 11. The other generator is coupled to the input circuit as shown.

In Fig. 3, generators f_1 and f_2 are both coupled to the output circuit of the tube 1 by means of the transformers 12 and 13 respectively.

In case the doubly modulated wave is transmitted the sending stations shown in Figs. 1, 2 and 3 are adapted to be used in connection with a receiving system employing two detectors in tandem, for instance as shown and described in the publication by Miessner on Radiodynamics above referred to.

What is claimed is:

1. A signaling system comprising means for supplying high frequency waves, means for supplying other high frequency waves of different characteristic, means for modulating said first mentioned waves in accordance with a signal, said modulating means also serving to modulate said other waves in accordance with the first mentioned modulated waves, a transmitting conductor, and means for impressing the said modulated waves on said transmitting conductor, said means being so positioned that at least one of the said high frequency waves will not be impressed on the transmitting conductor.

2. A signaling system comprising means for supplying waves, means for supplying other waves of different frequency, and means for modulating each of said waves in accordance with the signal, said modulating means being in common to both of said supplying means and coupled with a transmitting conductor.

3. A signaling system comprising means for supplying waves, separate means for supplying other waves, and a vacuum tube device for simultaneously modulating each of said waves in accordance with a signal.

4. A signaling system comprising means for supplying waves, means for supplying other waves, having a different characteristic, and a vacuum tube device for modulating individually and collectively the waves derived from said supplying means.

5. A signaling system comprising means for supplying waves of relatively high frequency, means for supplying waves of relatively low frequency, and a vacuum tube of the audion type for modulating said waves of both frequencies in accordance with a signal, said vacuum tube also serving to modulate said waves of high frequency in accordance with the modulated waves of low frequency.

6. A signaling system comprising means for supplying waves of high frequency, means for supplying waves of low frequency, means for modulating said waves of low frequency in accordance with a signal and for modulating said waves of high frequency in accordance with the modulated lower frequency waves, and a transmitting conductor energetically associated with said modulating means and so positioned that at least one of said high frequency waves is not impressed by a source on said conductor.

7. A signaling system comprising means for supplying waves of high frequency, means for supplying waves of low frequency, a source of telephone currents, and a vacuum tube device for modulating said waves of low frequency in accordance with the telephone signal and for modulating said waves of high frequency in accordance with the modulated lower frequency waves.

8. A signaling system comprising a plurality of means for supplying waves of different characteristic, a modulator in circuit between two of said means, for modulating each of said waves in accordance with a signal, and a transmitting conductor coupled with the circuit which includes one of said means.

9. A signaling system comprising a plurality of sources of high frequency waves, a vacuum tube device between two of said sources for modulating the waves derived therefrom, and a signaling device associated with said tube for controlling said waves.

10. A vacuum tube of the audion type having an input circuit and an output circuit, an alternating current generator and a source of signal current for supplying potential variations to said input circuit, a source of direct current in said output circuit, and means for supplying an alternating current to said output circuit of different frequency than that supplied by said alternating current generator.

11. Transmitting apparatus comprising means for producing electric currents of different frequencies interacting to produce beats, means for simultaneously modulat-

- ing the amplitudes of said currents in accordance with a signal or message, and means for impressing the beat energy upon a transmitting medium.
- 5 12. The method of impressing upon a transmitting medium electrical energy representing a signal or message, which consists in producing electric currents of different frequencies interacting to produce beats, simultaneously changing the amplitudes of said currents in accordance with the signal or message to be sent, and impressing the beat energy upon the transmitting medium.
- 15 13. Transmitting apparatus comprising means producing electric currents of different frequencies interacting to produce beats of inaudible frequency, telephonic apparatus simultaneously modulating the amplitudes of said currents, and means for impressing the beat energy upon a transmitting medium.
- 25 14. The method of impressing upon a transmitting medium electrical energy representing a signal or message, which consists in producing electric currents of different frequencies interacting to produce beats of inaudible frequency, simultaneously changing the amplitude of said currents in accordance with the signal or message to be sent, and impressing the beat energy upon the transmitting medium.
- 35 15. In a signaling system, means for producing a signal current, an intermediate frequency current and a high frequency current, means for modulating the intermediate and the high frequency currents according to the signal current, and means for simultaneously modulating the high frequency current according to the intermediate modulated current.
- 45 16. In a signaling system, means for producing a high frequency current, means for producing a signaling current, means for modulating the high frequency current directly in accordance with the signaling current, and means for modulating the high frequency current indirectly as a function of the signaling current.
- 50 17. In combination, means for producing a carrier current, and means for varying a characteristic of the carrier current in two distinct ways either of which may be utilized independently of the other for reproducing the same sound.
- 55 18. In combination, means for producing a carrier current, means for varying a characteristic of the carrier current in two distinct ways, one of which may be utilized for reproducing a signal by a single detection and the other of which may be utilized for reproducing a signal by plural detection.
19. The method of signaling which comprises producing a signal current, an intermediate frequency current and a high frequency current, modulating the intermediate and high frequency currents according to the signal current, and simultaneously modulating the high frequency current according to the intermediate modulated current.
20. The method of signaling which comprises causing a plurality of distinct but simultaneous series of variations in a carrier current by a single signal.
- 25 21. The method of signal transmission which comprises producing a carrier current, varying a characteristic of the carrier current in a plurality of distinct ways in accordance with sound, any of which may be utilized to reproduce the same sound at another station.
- 30 22. In combination, means for producing a carrier current, a single source of modulating waves for varying said current, and means whereby said source varies a characteristic of the said current in two distinct ways, either of which may be utilized independently of the other for receiving the same signal.
- 35 23. A system comprising a source of relatively high frequency waves or impulses, a source of relatively low frequency waves, and means whereby the waves or impulses produced from said first mentioned source are caused to vary in amplitude in two distinct ways, either of which may be utilized independently of the other to reproduce waves similar to those from said second mentioned source.
- 40 24. A system comprising a source of periodic energy of relatively high frequency, a second source of periodic energy having a relatively low frequency, and means whereby the energy produced by said first mentioned source is caused to vary in intensity in a plurality of distinct ways, any one of which may be utilized to reproduce periodic energy similar to that produced by said second mentioned source.

In witness whereof, I hereunto subscribe my name this 31st day of October A. D., 1917.

WILLIAM E. BEATTY.
